CLAIM

(**) Term: **15 Years**

The ornamental design for a rear combination lamp for an automobile, as shown and described.

(21) Appl. No.: **29/663,219**

DESCRIPTION

(22) Filed: **Sep. 13, 2018**

FIG. 1 is a front elevational view of a rear combination lamp for an automobile in accordance with a first embodiment of our new design;

(30) **Foreign Application Priority Data**

FIG. 2 is a rear elevational view thereof;

Mar. 15, 2018 (JP) 2018-005510

FIG. 3 is a top plan view thereof;

(51) **LOC (12) Cl.** **26-06**

FIG. 4 is a bottom plan view thereof;

(52) **U.S. Cl.**

FIG. 5 is a left side elevational view thereof;

USPC **D26/28**

FIG. 6 is a right side elevational view thereof; and,

(58) **Field of Classification Search**

FIG. 7 is a front side perspective view thereof.

USPC D26/28-36, 139

The rear combination lamp for an automobile is configured

CPC F21S 48/00; F21S 48/10; F21S 48/115;

to be mounted to an automobile. The mounting structure and

F21S 48/225; F21S 48/1233; F21S

support structure of the rear combination lamp for an

48/1266; F21S 48/1388; F21S 48/2268;

automobile, shown in broken lines in FIGS. 1 to 7, form no

F21V 21/04; B60Q 9/13; B60Q 9/135;

part of the claimed design since the mounting structure and

B60Q 9/1375

support structure are hidden when the rear combination lamp
